CLAIM

The ornamental design for a display screen with a computer-generated electronic panel for providing rating feedback for a computing device, as shown and described.

DESCRIPTION

The single FIGURE is a front view of a display screen with a computer-generated electronic panel for providing rating feedback for a computing device showing my new design. The broken lines shown in the drawings are for the purpose of illustrating a display screen of a computing device, text, and other images, and form no part of the claimed design.
